LOOSE-LEAF BINDER

John Schade, Holyoke, Mass., assignor to
 National Blank Book Company, Holyoke,
 Mass., a corporation of Massachusetts

Application July 31, 1935, Serial No. 33,968

11 Claims. (Cl. 129—38)

This invention relates to an improvement in loose leaf binders. Its particular object is to improve that type of binder used to hold a group of pamphlets. This broad type is so well known that I will proceed at once to disclose the detail features of my construction by which certain improvements are attained, all as will be pointed out and claimed.

10 In the drawings, Fig. 1 is an inside plan view of the open binder; Fig. 2 is a section on line 2—2 of Fig. 1; Fig. 3 is an end view looking up in Fig. 1; and Figs. 4, 5, and 6 are detail views of parts.

15 A suitable binding case is represented by the reinforced curved back panel 2 and hinged covers 1. The particular embodiment of the invention as disclosed has a metal plate 3 with edge flanges 4 fastened on the inside curved face of the back panel 2. This plate 3 has a set of spaced posts 5 rigidly mounted with screw threaded recesses to receive screws 6. On plate 3 I mount an angular plate 7. This plate as shown consists of two equal flat sides meeting at an angle in the center of the book. The screws 6 hold the plate 7 in place 25 with heads in countersunk relation to the top of the plate and shanks threaded in posts 5. At the outer edges of plate 7 I preferably bend flanges 8 downwardly about as shown to make good contact with the back panel just inside the hinge lines. These flanges 8 with flanges 4 give very good support to the angle plate 7 at the sides.

30 The space between plate 7 and plate 3 is closed at the upper and lower ends of the book. I prefer to make the closure at one end by a permanent closure plate 9, and at the other end by a hinged plate 10 to be readily opened and closed as a door, and with a spring latch 11 to normally hold plate 10 in closed position.

35 The hinged closure is seen in Figs. 3, 5, and 6. It consists of a single stamping with studs 12 which may pivot in corresponding holes in flanges 4. A spring tongue 11 may be struck up out of plate 3 to serve as latch 11 in the manner clearly indicated in Figs. 3 and 5. It will be seen that plate 10 will act as a closure in the position of Fig. 3 for that end of the space between plates 3 and 7 of Fig. 2, and this closure may be opened on hinges 12 by turning it, the spring latch 11 acting in the position of Fig. 5 to keep the door closed. I prefer to have the door at the top of the book, but of course it may be at either end.

40 I provide a partitioned hood at each end of plate 7. The hood 13 may be made as part of end closure plate 9 fastened permanently to the plate

7 in any suitable way. This is shown in Fig. 4. The partitions 14 of the hoods may be made by striking up metal from plate 7 or in other suitable ways. The hood 15 may be made by a strip of metal permanently fastened in any suitable way to plate 7 in the position of Fig. 2. The plate or door 10 forms the outer closure for the partitioned spaces, as plate 9 does for hood 13.

45 The parts shown in Fig. 4 comprising principally plate 7 are fastened to the plate 3 by screws 6 after plate 3 of Fig. 5 is fastened to the back panel. Or posts 5 may be mounted permanently on the back panel and the whole assembly of Fig. 6 fastened by screws 6 to posts 5. When the structure is made up into book form the general 50 operation is as follows: The pamphlets are placed one by one with their back folds against plate 7. With end door 10 open, a straight wire 16 is passed between the leaves of each pamphlet. The ends of wires 16 are then located inside the hoods 13 and 15 and when the door 10 is closed and latched the pamphlets are bound. A reserve supply of wires 16 is conveniently held in the space between plates 7 and 3 to which access is had when the door 10 is open.

55 In my improved construction I provide for holding only a few pamphlets or many pamphlets, as occasion may arise in the use of the binder. In holding a few, say four thin pamphlets, one may be held by each wire 16 and each wire placed between partition walls 14, as in Fig. 2. This will hold them in loose, spread-out arrangement, very easy for individual examination, as they cannot crowd together when the binder is open. Each wire 16 holds its pamphlet securely in the binder, yet with a substantial freedom of movement. Partition walls 14 limit the movement of each wire so its ends cannot work out from under end hoods 13 and 15, as they could but for the partition walls. The advantage of having such substantial freedom is that the wires are not liable to cramp. Each one may shift freely between the partition walls, but not enough to work out. The proportion and construction should be such as to provide for such free action at the back of the book. This is one reason I make the angle plate 7 flat sided. It gives rod 16 a freedom of movement. With only a few pamphlets in the binder, each one is very easily examined and the others moved out of the way, without getting any of their holding wires jammed.

60 When the binder is fairly well filled with pamphlets, there is this advantage: Partition walls 14 keep the pamphlets fairly well separated

and balanced so that they cannot all crowd over to one side. One-half may be bound above one flat side of plate 7, and the other half on the flat other side. The angle between these two sides 5 increases the capacity of the book by making the two flat sides longer than if a single flat side were used the width of the back panel. The angle is such that the pamphlets when opened will lie out substantially flat. When my binder 10 is opened, there is a distinct tendency for the filling material to fall down on each cover in well balanced condition. The back binding is loose enough to provide for this. Each half at the back is free to slide down the inclined flat side against 15 the adjacent cover. And yet those from one side may be picked up and laid over on the other side. With their loosely held back wires, the manipulation of the filler and its parts is very convenient.

20 Having disclosed and described my improved binder, I claim:

1. In a binder of the kind described having a back panel and hinged covers, the combination of an angle plate attached above the back panel 25 and having two flat sides with the angle above the center line of the back panel, a narrow hood portion at each end of said angle plate, said hoods having cross partitions, retaining wires adapted to extend from hood to hood and be held 30 adjacent said flat sides for free lateral movement thereon but limited by said cross partitions from sliding too far askew on the angle plate to work loose from the binder.

2. In a binder of the kind described having 35 covers hinged to a back panel, the combination of a flat sided angle plate having its area covering the inside of the back panel and spaced above the latter, the upper surface of said plate being flat sided and pitched downwardly from the center toward the sides, means located at opposite 40 ends of said angle plate to retain wires running from one end to the other, said retaining means being loose enough to permit the wires to slide freely on said plate.

45 3. A binder comprising covers hinged to a back panel, an angle plate of two flat sides angularly arranged to span the space between the hinge lines with a slight downward pitch from the center line toward each cover, retaining wires for pamphlets adapted to slide freely down said flat sides, and means at the opposite ends of the binder to hold said wires loosely in relation to said plate.

4. The binder of claim 3 in combination with 55 means to limit the movement of the retaining wires on the downwardly pitched flat sided plate.

5. The binder of claim 3 in combination with means to prevent said retaining wires from passing the center line of said plate.

60 6. A binder comprising a back panel and covers hinged thereto, means mounted at the opposite ends of the back panel to loosely retain the ends of wires whereby pamphlets may be bound, an angle plate mounted on the inside and above the back panel to hold the wires and bound pamphlets for easy and free movement at the back,

said angle plate having flat sides oppositely pitched from the center line and means to stop the wires from traveling across said plate from one pitched side to the other or more than a part of the way on each side.

7. A binder of the kind described including a back panel, hinged covers connected thereto, and means to hold pamphlets loosely between the covers, said means consisting in a wire to be placed in the fold of each pamphlet, a support 10 spanning the back panel for the pamphlet backs to rest and slide against, said support having two oppositely pitched flat sides arranged to facilitate pamphlets sliding down some against one cover and some against the other cover when the book is opened, cages one at each end of the back panel to retain the ends of the retaining wires from falling out, said cages having retaining means to allow very free shifting of the wire ends between predetermined limits without binding. 15

8. The combination of a curved back panel plate having side flanges, a spaced covering plate made with two flat equal sides like a pitched roof and having side flanges toed over the flanges of the back panel plate, means to fasten said plates together, a cage extending across each end of the covering plate with partitions between which binding wires are adapted to lie for free but limited movement across the plate, end closing plates, one of which is hinged, to cover the space 30 between said plates and the outside openings of said cages.

9. In a binder of the kind described having a back panel and a supporting plate attached on the inside of the back panel of the binder, said 35 plate having side edges braced against the edges of the back panel and two flat sides pitched at a slight rise to meet in the central plane of the book, wires for loosely holding pamphlets with their backs resting on said flat sides and means at the ends of said plate to retain said wires in the book, said means comprising large pockets relative to the diameter of the wires to allow for substantial but limited movement for the ends of the wires in every direction except endwise 40 of the wires.

10. In metallic loose leaf mechanism for book binders the combination, of a stiff panel plate to lie on the inside face of a back panel, an angle plate fastened in rigidly supported position above 50 the panel plate and in spaced relation thereto, a hood at each end of the angle plate to hold wires from working loose when their ends are mounted under said hoods, end closure plates for the hoods, said angle plate being formed with oppositely pitched flat sides meeting in the central plane of the structure, all constructed and arranged to permit free limited movement of pamphlets bound by wires on said structure and without cramping the wires.

11. The structure of claim 10 in combination with partitions in said hoods to prevent movement from one flat side of the angle plate to the other, of wires binding pamphlets in said structure.

JOHN SCHADE.
